UNITED STATES PATENT OFFICE.

EMIL GATHMANN, OF BALTIMORE, MARYLAND.

INGOT MOLD.

Application filed October 16, 1925. Serial No. 62,755.

To all whom it may concern:

Be it known that I, EMIL GATHMANN, a citizen of the United States, residing in Baltimore city, State of Maryland, have invented certain new and useful Improvements in Ingot Molds, of which the following is a specification.

This invention relates to ingot molds of the kind in which the mold chamber has a bottom opening closed by a plug while casting and which is stripped or has the ingot removed from the mold by forcing the plug into the mold cavity so as to raise the ingot to a sufficient extent to permit it to be engaged by lifting devices which withdraw it from the mold. In such molds, the plug not only serves as a bottom closure for the mold cavity, but receives the impact of the molten metal while being poured into the mold. In big-end-up molds of the Gathmann type, or those in which the mold cavity is wider at top than at bottom and gradually tapers toward the bottom, the ingot is moved out of contact with the side walls of the mold cavity when loosened or raised by the plug and thus the ingot is easily lifted from the mold by lifting tongs or other lifting devices.

These sealing plugs are generally made of such refractory material as fire clay and heretofore have been made quite long, their length being considerably greater than their width. It has been found to be difficult to make such long plugs in such manner that they shall be true and even throughout their entire surface, imperfections often occurring here and there which prevent a close fit of the plug in the bottom opening of the mold. When this is the case the molten metal often leaks down between the sides of the opening and the sides of the plug, forming fins which interfere with the movement of the plug during stripping and also prevent free contraction of the ingot metal while solidifying, resulting in cracks in the lower part of the ingot which necessitate a considerable discard in the bloom rolled from the ingot. Generally the bottom opening has tapered walls and heretofore it has been difficult to obtain exact dimensions of the plug relatively to the diameters of the bottom opening.

I have found that by employing a shorter plug or one having a relatively short contacting surface with the walls of the bottom opening, these objections are overcome.

Such a plug may have its contact surface molded with greater accuracy than where the plug is long or has an extended contact surface. It is of course, important that where the contact surface is relatively small, some means should be provided for giving the necessary strength to the plug and this may be done by providing the plug with a bottom portion, the peripheral wall of which is of such diameter that it does not come in contact with the side walls of the bottom opening of the mold, but this lower portion may be made sufficiently large, strong and heavy to give to the plug as a whole sufficient strength and stability to support the molten metal and to receive the impact of the molten metal while being poured.

In carrying out my invention I make the plug much shorter than heretofore, the upper portion which comes in contact with the walls of the bottom opening being only sufficient to seal the opening and the plug as a whole is made of such length that it will stand the impact and pressure of the molten metal. Preferably the lower portion of the plug is tapered in such manner that its periphery is entirely out of contact with the walls of the bottom opening but this portion of the plug is of such size and strength as to reinforce the active or sealing portion of the plug.

In the accompanying drawings:

Figure 1 is a vertical central section of a Gathmann ingot mold with my improvements applied.

The drawing also shows a stool on which the mold is supported and a feeder or shrink head casing through which the molten metal is poured.

Figure 2 is a bottom plan view of the mold.

Figure 3 is a side elevation of the sealing plug.

Figure 4 is a top plan view thereof.

The mold A, which as before stated, is of the Gathmann type, rests on a stool S and it is provided with a feeder or shrink head casing B of any suitable kind. In this instance the mold is of the big-end-up type, the mold cavity C being wider at the top than at the bottom, the walls of the mold cavity gradually tapering to a point near the bottom of the cavity as indicated at x. The mold is tapered inwardly by suitable curves having suitable radii. The mold shown has a cavity, the major portion

of which is of general rectangular shape but at the bottom it is necked in so as to properly communicate with a central opening O , which is the bottom opening 5 of the mold and preferably has tapered side walls o as usual. The opening s in the stool is considerably wider than the bottom opening of the mold and when the mold is being stripped, the stripping mechanism 10 preferably operates through the opening s as is well understood in the art.

As before explained, sealing plugs have been heretofore used, but they have been quite long and had quite an extended bearing 15 or contact surface and it has been extremely difficult to obtain sealing plugs having peripheral contact surfaces which are true and even. This is largely because the plug as a whole is large and heavy and true 20 molding has been difficult. I have found that I can mold with greater accuracy and less expense a plug of relatively small length, that is a plug the length of which is much smaller than its width or diameter. A 25 plug of this description is illustrated in the drawings at P . This plug is more than twice as wide as its length. It has a peripheral inclined contact surface at p adapted to fit accurately the inclined side walls o or 30 the bottom opening of the mold. The plug is circular in plan as indicated in the drawings because experience has shown that the circular bottom opening for the mold is preferable. A plug having the upper portion 35 with peripheral inclined walls p would seal in a way the mold, but such a thin plug would not be able to stand the weight of metal or the impact of the metal poured into the cavity, therefore, it has been found 40 necessary to reinforce the plug and this has been done by providing it with a lower portion p' which in this instance is provided with inclined peripheral walls y which have a sharper incline than the walls p , so that 45 the walls y shall not come in contact with the side walls of the bottom opening of the mold. The precise dimensions vary with different molds. Where the bottom opening 50 of the mold is 12 inches in diameter at the top of the opening where it begins to taper and this bottom opening is $10\frac{3}{4}$ inches in diameter at the bottom, the diameter of the top of the plug is preferably made $11\frac{3}{4}$ inches so that the plug will sink to a short 55 distance within the bottom opening. The peripheral contact surface in the plug shown tapers from a diameter of $11\frac{3}{4}$ inches to a diameter of $11\frac{1}{4}$ inches and the diameter of the reinforcing part p' at its lower end is 60 $10\frac{1}{2}$ inches. These dimensions give the best results in a mold of the kind shown having a 12-inch diameter bottom opening, tapering to a diameter of $10\frac{3}{4}$ inches but these 65 dimensions are not obligatory, they are largely relative and are changed consider-

ably when the invention is applied to different kinds of molds.

It will be observed that in the construction shown the maximum diameter of the plug is somewhat less than the maximum diameter of the bottom opening of the mold in order that the plug shall not project above the top of the bottom opening or into the lower part of the mold chamber. If the plug should project into the mold chamber 75 it would cause a loss of ingot metal due to the inclusion of the plug material in the bottom of the ingot cast and hence lessen the percentage of sound saleable product which may be obtained from the ingot. In 80 other words, if the plug is included in the casting at the bottom of the ingot, it is necessary to crop just that much of the bottom portion of the ingot which is a loss in manufacture. The plug is preferably so 85 dimensioned that the vertical height or thickness thereof is such that when the plug is seated in the bottom opening of the mold its lower surface will extend above the bottom of the mold. This arrangement prevents an accidental loosening of the plug from its seat in the bottom opening of the mold when the mold as a whole is placed 90 on a flat solid stool. In other words, the preferable arrangement is such that the plug 95 when in use shall be seated entirely within the bottom opening of the mold, its lower end being appreciably above the lower end of said bottom opening and its upper end being appreciably below the top of said 100 bottom opening. This arrangement cooperates advantageously with a mold of the kind shown in which the lower portion of the mold walls are necked-in and in which 105 there is a concavo-convex formation of the walls of the mold cavity or chamber above the top of the bottom opening of the mold.

Another feature of the invention which may be mentioned is that in stripping the mold there is less friction than would be incident to the use of a plug of usual length and if the plug adheres to the ingot when it is stripped, there is less material to be 110 cropped at the lower end of the ingot.

I claim as my invention:

1. A sealing plug for ingot molds formed with a peripheral contact surface, the diameter of which is materially larger than the length of the plug, and which is reinforced by a lower portion of reduced diameter having no contact surface.

2. A sealing plug for ingot molds having an upper portion formed with an inclined peripheral contact surface, the diameter of which is materially greater than its length, and a lower non-contacting peripheral portion of less diameter than the upper part of the plug.

3. A sealing plug for ingot molds having an upper circular portion formed with an

inclined peripheral contact surface, the diameter of which is materially greater than its length, and a lower tapered non-contacting peripheral portion of less diameter than the upper part of the plug.

4. The combination with an ingot mold having a bottom opening, of a sealing plug having an upper portion formed with an inclined peripheral contact surface, the diameter of which is materially greater than its length, and a lower non-contacting peripheral portion of less diameter than the upper part of the plug, the plug as a whole being materially greater in width than in length.

5. The combination with an ingot mold having a necked-in lower portion with concavo-convex walls and a circular bottom opening with inclined walls, of a sealing plug having an upper portion formed with an inclined peripheral contact surface, the

diameter of which is materially greater than the length of the plug as a whole, and a lower non-contacting peripheral portion of less diameter than the upper part of the plug, the lower portion of said plug being seated to terminate short of the bottom of the mold opening.

6. An ingot mold having a chamber with a necked-in lower portion provided with concavo-convex walls, and a circular bottom opening having inclined walls, in combination with a sealing plug having an upper portion formed with an inclined peripheral contact surface, the diameter of which is materially greater than the length of the plug as a whole, and a lower non-contacting peripheral portion of less diameter than the upper part of the plug.

In testimony whereof, I have hereunto subscribed my name.

EMIL GATHMANN.
